L. R. RHODES

PNEUMATIC EARTH SCRAPER

Filed Nov. 10, 1920

Patented June 26, 1923.

1,459,748

UNITED STATES PATENT OFFICE.

LEIGH RANDALL RHODES, OF CLEVELAND, OHIO.

PNEUMATIC EARTH SCRAPER.

Application filed November 10, 1920. Serial No. 423,047.

To all whom it may concern:

Be it known that I, LEIGH RANDALL RHODES, a citizen of the United States, residing at Cleveland, in the county of Cuyahoga and State of Ohio, have invented certain new and useful Improvements in Pneumatic Earth Scrapers, of which the following is a specification.

The present invention relates to an earth cutting or excavating tool, and has for its object to provide a portable device of this character which is power driven and embodies novel features of construction whereby it can be used to advantage under many conditions where it would not be practical to employ a larger device, as when tunneling or otherwise operating in close quarters.

Further objects of the invention are to provide an earth cutting or excavating implement of this character which is comparatively simple and inexpensive in its construction, which can be operated without difficulty in close quarters, which can be used effectively upon earth which is so hard that it could only be operated upon with difficulty by a hand tool, and which will result in increased efficiency and lower costs in many tunneling or excavating jobs where hard earth is encountered and work with a hand tool would be very difficult.

With these and other objects in view the invention consists in certain combinations, arrangements and associations of the parts, as will more fully appear as the description proceeds, the novel features thereof being pointed out in the appended claims.

For a full understanding of the invention reference is to be had to the following description and accompanying drawings, in which:

Figure 1 is a perspective view of a power driven earth cutting implement which is constructed in accordance with the invention;

Figure 2 is a side elevation thereof, showing the same in operation;

Figure 3 is a side elevation of the implement with portions broken away and shown in section to illustrate more clearly the details of construction;

Figure 4 is a transverse sectional view on the line 4—4 of Figure 2, looking in the direction of the arrows; and

Figure 5 is a transverse sectional view on the line 5—5 of Figure 3, looking in the direction of the arrows.

Corresponding and like parts are referred to in the following description and indicated in all of the views of the drawing by like reference characters.

Referring to the drawing, which illustrates one of many possible embodiments of the invention, the numeral 1 designates a knife blade which may have one edge thereof sharpened, as indicated at 1^a, and which is bent longitudinally so as to have a bowed formation. Side bars 2 are secured to the ends of the knife 1 and project laterally therefrom in a plane at substantially right angles to that of the blade, said side bars converging toward each other and being connected at their converging ends by a cross head 3. An anvil or head 4 is carried by the cross head 3 and engaged by a power driving tool such as the pneumatic hammer 5. This pneumatic hammer is shown as arranged in the plane of the frame of the tool, and the said frame is disposed at substantially right angles to the plane of the bowed blade 1, although the blade cuts in the direction of the frame. The pneumatic hammer may be held in position by cross bars 6 which connect the side bars 2 and are arranged upon opposite sides of the hammer. These cross bars thus serve both to retain the hammer in position and to strengthen and reinforce the frame. The mouth of the hammer fits loosely over the anvil 4 so that the reciprocating piston element 7 of the hammer will strike successive blows upon the anvil when the hammer is in operation. A lug 8 is shown as projecting laterally from the hammer and arranged to engage one of the cross bars 6 for co-operation therewith to hold the hammer in proper position upon the anvil 4 when the tool is in operation. The cross head 3 may be provided with a handle 9 for convenience in handling and manipulating the tool when placing it in working position or removing it therefrom. The usual compressed air supply pipe 10 is shown as connected to the handle of the pneumatic hammer in the usual manner.

In the operation of the tool the curved or bowed blade 1 which projects laterally from the frame is caused to enter the earth substantially as indicated by Figure 2, with the frame arranged adjacent to the surface of the earth. When the pneumatic hammer is operated the blows thereof will forcibly move the blade through the earth in the di-

rection of the frame and by manually manipulating the frame the blade can be kept in proper working position and guided through the earth in the desired manner. A 5 power driven tool of this character will operate quickly and economically upon earth formations which are so hard that work with a hand tool would be very slow and difficult. Furthermore, the tool is light in 10 weight and compact in its design so that it can be easily carried from place to place and used to advantage in close quarters where it would not be possible to use a large tool. The tool will be found especially valuable 15 in tunneling operations, although it may be used to advantage wherever a small power driven earth scraper or excavator is desired. The anvil 4 is preferably removable so that it can be readily replaced from time to time 20 as may be necessary, and in the present instance it is shown as having one end thereof fitted in the opening in the cross head 3 and clamped in position by a set screw 11.

While one particular embodiment of the 25 invention has been shown and described in detail for illustrative purposes, it will be understood that many changes and modifications are possible in carrying the invention into practice and that I do not restrict 30 myself to the exact construction illustrated by the drawing.

Having thus described my invention, what 35 I claim as new and desire to secure by Letters Patent is:—

1. A portable hand controlled earth excavating device of the character described, including an earth scraping blade, a frame carrying the blade and providing a means for pulling the blade through the earth, and 40 a power operating driving element mounted upon and carried by the frame.

2. A portable hand controlled earth cutter including a frame, a blade projecting laterally from the frame and operating in 45 the direction parallel thereto, and a power operated driving element mounted upon the frame, the frame and associated parts being adapted to be manually supported and handled as a unit.

3. An earth cutter including a flat frame, a blade projecting laterally from the frame and operating in the direction thereof, an anvil element upon the frame, and a power hammer engaging the anvil element and 55 mounted upon the frame.

4. An earth cutter including a bowed

blade, a frame carrying the bowed blade and arranged in a plane at an angle to the plane thereof, and a power hammer mounted upon the frame. 60

5. An earth cutter including a bowed blade, a flat frame carrying the blade and arranged in a plane at an angle thereto, an anvil element upon the flat frame, and a power hammer engaging the anvil element 65 and mounted upon the flat frame in the plane thereof.

6. An earth cutter including a bowed blade, side bars connected to the ends of the bowed blade, a cross head connecting the 70 side bars, an anvil element upon the cross head, a power hammer engaging the anvil element, and means for supporting the power hammer between the side bars.

7. An earth cutter including a bowed blade, side bars connected to the ends of the bowed blade, a cross head connecting the side bars a handle at the ends of the side bars, an anvil element on the cross head, a power hammer engaging the anvil element, and 75 cross bars connecting the side bars and holding the power hammer in position.

8. A portable hand controlled earth cutter including a power hammer, and a blade offset laterally from the power hammer and operating parallel thereto, the power hammer and blade being mounted to be manually supported and handled as a unit. 85

9. A portable hand controlled earth cutter, including an earth cutting blade having a cutting edge of comparatively large dimensions so as to work quickly through earth formations, and a power hammer for the blade, the power hammer and blade being mounted to be manually supported and 90 handled as a unit. 95

10. A portable hand controlled earth cutter including a frame, a bowed blade having the curved portion thereof offset laterally from the frame, and power driving means on the frame, the frame and associated parts being adapted to be manually supported and handled as a unit. 100

11. A portable hand controlled earth cutter, including a bowed blade having a curved edge portion, a portable frame supporting the blade, and power drive means on the frame, the frame and associated parts being adapted to be manually supported and handled as a unit. 105

In testimony whereof I affix my signature.

LEIGH RANDALL RHODES.
